[57] CLAIM

The ornamental design for a temperature sensing strip, substantially as shown and described.

DESCRIPTION

FIG. 1 is a front perspective view of a temperature sensing strip showing my new design;

FIG. 2 is a rear perspective view thereof;

FIG. 3 is a top plan view, the bottom plan view is a mirror image thereof;

FIG. 4 is a left end elevational view thereof; and,

FIG. 5 is a right end elevational view.

FIG.3

FIG.4
